L. H. PRAY.
UNIT SYSTEM FOR PLAYER PIANOS,
APPLICATION FILED AUG. 10, 1920.

1,401,730.

Patented Dec. 27, 1921.

UNITED STATES PATENT OFFICE.

LOUIS H. PRAY, OF MEDFORD, MASSACHUSETTS.

UNIT SYSTEM FOR PLAYER-PIANOS.

1,401,730.

Specification of Letters Patent. Patented Dec. 27, 1921.

Application filed August 10, 1920. Serial No. 402,648.

To all whom it may concern:

Be it known that I, LOUIS H. PRAY, a citizen of the United States of America, and a resident of Medford, in the county of Middlesex and State of Massachusetts, have invented certain new and useful Improvements in Unit Systems for Player-Pianos, of which the following is a specification.

This invention relates to player pianos and has for its object the provision of means adapted to be adjusted to any make and size of upright piano whereby such piano may be provided with an automatic player system.

15 The invention consists primarily in an adjustable support to be secured to the interior of a piano and a plurality of units adjustably mounted on said support, the number of units being equal to number of keys in 20 the piano and each unit consisting of self-contained mechanism for actuating a hammer coacting with one of the strings of the piano action.

25 The invention consists further of the means for securing said units to said support.

30 The invention consists also in certain novel features of construction and arrangement of parts which will be understood readily by reference to the description of the drawings and to the claims to be hereinafter given.

35 For the purpose of illustrating the invention, one preferred form thereof is illustrated in the drawings, this form having been found to give satisfactory and reliable results although it is to be understood that the various instrumentalities of which the invention consists can be variously arranged 40 and organized and the invention is not limited to the precise arrangement and organization of these instrumentalities as herein shown and described, except as required by the scope of the appended claims.

45 Of the drawings—

Figure 1 represents a side elevation of a unit embodying the principles of the present invention applied to a supporting bar shown in section.

50 Fig. 2 represents a vertical section of the same.

Fig. 3 represents a horizontal section on line 3, 3, on Fig. 2.

55 Fig. 4 represents a horizontal section on line 4, 4, on Fig. 2.

Fig. 5 represents a plan of a portion of the supporting bar and the supports therefor showing a unit secured to said bar, and

Fig. 6 represents a front elevation of the same, portions of which are shown in section.

Similar characters indicate like parts throughout the several figures of the drawings.

In the drawings, 10 is a metal bar provided with a longitudinal V-shaped upward bend 11 extending longitudinally thereof.

The front edge of said bar is provided with a downwardly extending flange 12 while the rear edge thereof is provided with a downwardly extending L-shaped flange 13.

This bar may be cut in any suitable length to accommodate it to various styles and sizes of pianos.

Each end of the bar 10 is provided with a slot 14 preferably extending to the outer end thereof.

Positioned in the slot 14 is a clamping bolt 15 mounted in the horizontal portion of 16 of a bracket 17 having a vertical slot 18 80 therein.

In the vertical slot 18 are one or more clamping members 19 mounted in the fixed member 20 which may be the side wall of a piano or a portion of a framework mounted in said piano.

By means of this construction the supporting bar 10 may be adjusted vertically to locate it properly for the actuating parts of the piano action.

90 By adjustment of the supporting bar on the end brackets 16, 17, the bar may be accommodated to various lengths of pianos.

When once adjusted the supporting bar 10 is securely clamped to the horizontal portion 16 of the bracket 17 and the said brackets 17 are securely clamped to the members 20 at the opposite ends of the piano.

100 Only one end of the bar and its supporting bracket is shown in the drawings, it being believed to be unnecessary to show the entire length and the construction at the opposite end as this construction is simply a duplication of the construction shown in Figs. 5 and 6 of the drawings.

The front flange 12 of the supporting bar 10 is adapted to be positioned in a transverse slit 21 in the upper face of a block 22 while the horizontal portion of the rear 110

L-shaped flange 13 is adapted to extend into a groove 23 in the rear end of the block 22.

The upper face of the block 22 has secured thereto, a pad 24 of felt or some similar yielding substance which pad extends over the end of the said block and into the upper part of the groove 23 as indicated in Fig. 2 of the drawings.

10 When the block is positioned relatively to the supporting bar 10 as indicated in Figs. 1 and 2 of the drawings, the pad 24 is slightly compressed and thereby causes sufficient friction between the two members to prevent one accidentally moving relatively to the other.

By means of a screw or other holding member 25, a spring clip 26 is secured to the upper face of the forward end of the 20 block 22, this clip extending toward the rear of the block 22 and being adapted to engage with the highest part of the V-shaped bend 11 thereby firmly retaining the block 22 in position on said supporting bar 10.

The blocks 22 may be adjusted longitudinally of the supporting bar 10 and when moved into any desired position thereon they are retained in such adjusted position 30 by means of the spring clip 26 and the front and rear flanges 12 and 13.

When it is desired to remove the block from the supporting bar, a downward pressure upon the front end of the block will 35 cause the spring clip 26 to yield sufficiently to allow the front flange 12 to be removed from the transverse slit 21 and when said flange has been removed, a forward pull upon the block 22 will disengage the block 40 from the L-shaped rear flange 13.

It is obvious therefore, that the blocks 22 may be moved upon the supporting bar into any desired position to accommodate them to the various styles of piano actions and 45 retained in adjusted position without using securing screws or other members which must be removed when it is desired to remove a block for any reason.

Each block is a separate unit and may be 50 removed from the supporting bar without disturbing any of the other units and as means is provided whereby such removal may be made toward the front of the piano, the other parts of the operating device will 55 not be disturbed.

The block 22 itself is preferably made up of a plurality of layers of material.

The upper layer 27 of the block 22 is provided with a cylindrical port 28 opposite the 60 V-shaped bend 11 in the supporting bar 10.

Air is adapted to enter through the port 28 into a chamber 29 formed in the layer 30 immediately beneath the layer 27.

This layer 30 has also formed therein a 65 passage 31 communicating with alined cylin-

drical openings 32 formed in the middle layer 33 and the lower layers 34 and 35.

The opposite end of the passage formed by said cylindrical openings 32 communicates with a bellows or pneumatic hinged 70 at 36 to the lower layer 35 and composed in part of a movable plate 37 connected to the edges of the lower layer 35 by means of a flexible member 38.

The rear end of the hinged movable plate 75 37 is provided with a projecting member 39 adapted to communicate with and actuate a vertical rod for operating the hammer of the piano action.

In the layer 33 and alined with the port 80 28 is a connecting port 40, the lower end of which communicates with a chamber 41 from the forward end of which extends a passage 42 communicating with a passage 43 in the upper end of which is a tubular 85 member 44 the upper end of which is adapted to receive a flexible tube 45 of rubber or some similar material, the opposite end of which extends to and communicates with the usual vacuum chest.

90 The upper face of the lower layer 35 is provided with a depression 46 with the forward end of which communicates a passage 47. A tubular metal pipe 48 communicates with the forward end of the passage 47 and 95 has an upward bend therein the upper end of which is adapted to receive one end of a flexible tube 49 of rubber or some similar material, the opposite end of which communicates with one of the openings in the 100 usual tracker board.

The upper end of the depression 46 is closed by a flexible diaphragm 50 secured at its edge to the upper face of the layer 35 and superimposed upon this diaphragm 50 and 105 preferably secured thereto is a stiffening plate 51 having an upwardly extending post 52, the upper end of which projects through the connecting port 40 with its extreme upper end slightly below the upper surface 110 of the layer 33.

This layer 33 has extending upwardly therefrom, a plurality of guide pins 53 between which is a disk valve 54, the upper and lower faces of which are faced with 115 rubber 55 as indicated in Fig. 2 of the drawings.

Between the passage 47 and the passage 42, is a port 56, the upper end of which is closed by a disk 57 having a small central vent as 120 shown in Figs. 2 and 3 of the drawings.

This vent is so located that it can readily be cleaned of dust or any other obstructions by removing the rubber tube 45 from the tubular member 44 and extending a needle 125 downwardly through said tubular member 44 into the vent 58.

This is of some importance as devices of this class are liable to become inoperative by being clogged with dust and it is de- 130

sirable to provide means for readily cleaning out the passages without disturbing the various operating parts.

By making the block 22 of a plurality of 5 laminated layers, the construction of the block is greatly facilitated as each layer may be quickly provided with the various ports, chambers and depressions and then all of the layers may be assembled and glued together 10 making a suitable block.

When these layers have been thus secured together, the sides thereof have glued there- 15 to, sheets 59 of fiber-board or some similar material.

15 The operation of the device is as follows:

A piano having been selected, the brackets 17 are secured to end frames 20 and adjusted vertically so that the supporting bars 10 will be at the desired height and these sup- 20 porting bars 10 are adjustably secured to the brackets 17 so that said bars extend the entire length of the piano.

While only one bar 10 is shown in the drawings, it is obvious that in installing the 25 player mechanism two supporting bars would be used one above the other.

A unit is then selected for each string of 30 the piano and these are mounted upon the supporting bars 10 and adjusted lengthwise thereof so that the member 39 of each unit will be in position to actuate a hammer actuating rod forming a part of the piano action.

The various units are then connected by 35 means of the rubber tubes 45 and 49 to the vacuum chest and the tracker board.

When thus connected and one of the 40 openings in the tracker board is uncovered or exposed, air will be admitted to the tubular member 48 and passing through the passage 47 and depression 46 will force the diaphragm 51 upwardly and thereby cause the post 52 to lift the valve 54 and close the port 28 while uncovering the port 40.

45 As a consequence of this lifting of the valve 54, a communication from the vacuum chest is made through the tubular member 44, passages 43 and 42, chamber 41, port 40, chamber 29, passages 31 and 32 to the 50 interior of the pneumatic or bellows 37-38 secured to the lower portion of the block 22.

The suction through these passages and chambers will thereupon cause the bellows to be collapsed and the projection 39 from 55 the rear end of the plate 37 will be consequently moved upwardly to actuate the hammer of the piano action.

When the tracker board opening is again covered, the pneumatic or bellows 37-38 60 returns to its normal position the air beneath the diaphragm 51 being discharged through the vent 58 thus permitting the dia- phragm 51 to move downwardly together with the post 52.

65 The lowering of the post 52 will permit

the valve 54 to drop into the position indicated in Fig. 2 of the drawings and then atmospheric air will pass through the port 28, chamber 29, passages 31, 32 into the interior of the bellows or pneumatic 37-38 70 returning the plate 37 of said pneumatic to its lowermost position as indicated in Fig. 2 of the drawings preparatory to another operation thereof.

This makes a simple construction of unit 75 which may be made economically and the means provided for mounting the various units upon a supporting bar is most effective.

It is believed that from the foregoing de- 80 scription, the operation and many advantages of the present invention will be readily understood.

Having thus described my invention, I 85 claim:

1. A supporting bar having a stiffening rib extending lengthwise of the top face thereof; and detachably secured thereto a plurality of hammer-actuating units adjustable endwise of said bar and each having 90 a spring member extending over and coacting with said stiffening rib.

2. A supporting bar comprising a plate having an upwardly extending reverse bend extending lengthwise thereof; and detach- 95 ably secured thereto a plurality of ham- mer-actuating units adjustable endwise of said bar.

3. A supporting bar having an inclined portion on its upper face and extending 100 lengthwise thereof; a plurality of hammer- actuating units; and a clamping spring se- cured to the forward part of each unit for retaining said unit in adjusted position on said bar, the free end of said clamping 105 spring extending over and coacting with the inclined portion of said bar.

4. A supporting bar having an L-shaped flange projecting downwardly from one edge thereof; a plurality of hammer-actuating 110 units, each having at one end thereof a slot to engage said flange; and a spring secured to each unit and engaging the upper part of said bar to retain said unit in adjusted position.

5. A supporting bar having an L-shaped flange projecting downwardly from one edge thereof and a downwardly extending flange at the opposite edge; a plurality of ham- 115 mer-actuating units, each having at one end thereof a slot to engage said L-shaped flange and a slit in its upper part to receive said downwardly extending flange; and a spring secured to each unit and engaging the upper part of said bar to retain said unit in 120 adjusted position.

6. A supporting bar having a longitudi- 125 nal flange at the rear edge thereof; a plu- rality of hammer-actuating units adapted to be adjusted independently lengthwise of 130

said bar, each unit having a depression in the rear end thereof to receive said rear flange; and a spring clip secured to the forward upper side of each unit and extending rearwardly in contact with said bar, whereby each unit may be moved independently toward the front of the piano and disengaged from said supporting bar.

7. A supporting bar having a longitudinal flange at the rear edge thereof and a downwardly extending flange at its front edge; a plurality of hammer-actuating units adapted to be adjusted independently lengthwise of said bar, each unit having a depression in the rear end thereof to re-

ceive said rear flange and a groove in the top thereof to receive the front flange; and a spring clip secured to the forward upper side of each unit and extending rearwardly in contact with said bar, whereby each unit may be moved independently toward the front of the piano and disengaged from said supporting bar. 20

Signed by me at 746-7 Old South Bldg., Boston, Mass., this 7th day of August, 1920.
